UNITED STATES PATENT OFFICE.

EDWARD HERBERT SMITH, OF MOUNT VERNON, OHIO, ASSIGNOR TO DICKELMAN-BOWERS MANUFACTURING COMPANY, A COPARTNERSHIP COMPOSED OF JOSEPH L. DICKELMAN, FRANKLIN M. BOWERS, AND LIZZIE H. DICKELMAN, OF FOREST, OHIO.

DESIGN FOR A DIE-SECTION.

SPECIFICATION forming part of Design No. 35,503, dated December 31, 1901.

Application filed November 26, 1901. Serial No. 83,818. Term of patent 14 years.

To all whom it may concern:

Be it known that I, EDWARD HERBERT SMITH, a citizen of the United States, residing at Mount Vernon, in the county of Knox and State of Ohio, have invented and produced a new and original Design for Die-Sections, of which the following is a specification, reference being had to the accompanying drawings, forming part thereof, in which—

Figure 1 is a perspective view, and Fig. 2 is a transverse section, of a die showing my new design.

The leading feature of my design consists in the design forming the subject-matter of the accompanying illustration.

As shown in the drawings, the die has a block A, provided in its upper face with parallel grooves A' A'', extending longitudinally parallel and spaced apart by the intermediate

upwardly-projecting ridge A³, the concave faces of the grooves A' being crossed transversely by the series of parallel grooves A⁴, which extend to the outer edges of said grooves and widen gradually from their inner toward their outer ends.

Having described my invention, what I claim as new, and desire to secure by Letters Patent, is—

The design for a die-section as herein shown and described.

In testimony whereof I have signed my name to this specification in the presence of two subscribing witnesses.

EDWARD HERBERT SMITH.
